(57) CLAIM

The ornamental design for a disc or card holder, as shown.

DESCRIPTION

FIG. 1 is a perspective view of a disc or card holder showing our new design;

FIG. 2 is a top plan view thereof, shown in a closed condition;

FIG. 3 is a perspective view thereof, shown disassembled;

FIG. 4 is a top plan view of the base component;

FIG. 5 is a side elevational view of FIG. 4, the opposite side being a mirror image;

FIG. 6 is a top plan view of the lid component; and,

FIG. 7 is a side view of FIG. 6, the opposite side being a mirror image.

The four lugs featured on the sides of the top of the disc or card holder as shown in FIGS. 1, 2, 3, 6, and 7 are for illustrative purposes only and forms no part of the claimed design.

1 Claim, 4 Drawing Sheets

FIG. 4

FIG. 6
